UNITED STATES PATENT OFFICE.

GEORGE J. PAGE, OF COLONY, KANSAS.

RUBBING-POST.

1,157,801.

Specification of Letters Patent. Patented Oct. 26, 1915.

Application filed April 16, 1913. Serial No. 761,440.

To all whom it may concern:

Be it known that I, GEORGE J. PAGE, a citizen of the United States, residing at Colony, in the county of Anderson and State 5 of Kansas, have invented certain new and useful Improvements in Rubbing-Posts; and I do hereby declare the following to be a full, clear, and exact description of the invention, such as will enable others skilled in 10 the art to which it appertains to make and use the same.

The object of this invention is the provision of a rubbing post adapted to contain, under adequate and uniform pressure, a 15 medicated grease to be wiped upon the flesh of a hog or other animal contacting therewith.

In the accompanying drawing, Figure 1 is a vertical sectional view through my im- 20 proved rubbing post, and Fig. 2 is a vertical sectional view as indicated by the section line 2—2 in Fig. 1.

Referring to the drawing, wherein similar reference characters correspond with similar 25 parts throughout the several views, the numeral 1 indicates a substantially L-shaped body comprising a hollow vertical stem and a plurality of laterally extending, communicating hollow branches and having an up- 30 per open end normally closed by a screw threaded cap 2. The horizontal portion is provided with laterally projecting ears 3 having apertures therethrough for receiving 35 screws or similar securing devices. Near the bottom of the vertical portion of the body, a plurality of laterally projecting extensions 4 is formed thereon and communicate with the interior thereof.

The ends of the extensions 4 are partially 40 closed by an annular, internal flange integral with the walls thereof, the edges of the said flange being shaped to conform to the contour of the surface of the balls 6 as shown at 5 to provide seats for the balls 6, said balls 45 are adapted to be normally held seated by the pressure of the medicated grease contained within the body portion. As the balls 6 of the extensions are seated in vertically disposed seats, it will be obvious that a force 50 exerted upon a horizontal or substantially horizontal line will unseat said balls and permit the contents of the body portion to escape. The horizontally disposed portion of the body is terminated in an upturned 55 end 7 partially closed at 5 to form a seat for

a ball 6 which is also adapted to be normally retained seated by the pressure of the contents of the body. As the lowermost ball 6 is seated against a horizontally disposed seat, it will be obvious that force exerted 60 upon a line vertical or substantially vertical will dislodge or unseat said ball and thus permit the contents to escape. Gutters 8 are formed in the outer ends of the extensions 4 and the upturned end 7 so as to hold a part 65 of the contents escaping from the body portion and thus prevent undue wasting of the material.

The contents of the body portion 1 is normally maintained under adequate pressure 70 by means of the handle rod 9 carrying a piston head 10 at its lower end, over which is disposed a suitable weight 11. The handle rod 9 projects through the cap 2 at the upper end of the body portion 1 and is provided 75 at its lower end with suitable threads for receiving nuts 12, between which the piston head 10 and weight 11 are securely clamped. It will be understood that the weight 11 disposed above the contents of the body portion 1 will normally maintain said contents under sufficient pressure to retain the balls 80 seated. It will be further seen that the weight, whether near the top or near the bottom of the vertical part of the body portion 85 will maintain the contents thereof under an entirely uniform pressure.

As shown, the lateral extensions are four in number and arranged at right angles to each other. However, I wish it to be understood that I contemplate various differences 90 in the numbers and arrangement of said extensions. The balls 6 project a short distance out of the ends of the extensions and turned end 7 and are adapted to be engaged and partially unseated by the contact of a hog therewith. As the greater part of the balls 6 are disposed within the body portion they will at all times be coated with the material therein, and as the animal brushes against 100 the posts the balls are rotated and the film of grease deposited thereon from the body portion is wiped off and upon the hide of the animal.

What I claim is:—

1. A rubbing post comprising a duct, a ball projecting beyond one end of the duct, and pressure exerting means arranged in the other end of the duct and operated by downward pressure on a semifluid substance con- 110

tained in the duct to hold the ball normally seated.

2. A rubbing post comprising a duct having a restricted opening at one end, a ball within the duct of the size to project partially through said restricted seat, and a piston in the opposite end of the duct operating by pressure upon a semifluid substance contained in the duct to hold the

ball normally seated in the restricted opening.

In testimony whereof I have signed my name to this specification in the presence of two subscribing witnesses.

GEORGE J. PAGE.
